UNITED STATES PATENT OFFICE.

JOSEPH ERNEST BARROWS, OF YARDLEY, ENGLAND.

CUE FOR BILLIARDS AND LIKE GAMES.

1,007,668.

Specification of Letters Patent. Patented Nov. 7, 1911.

Application filed April 29, 1911. Serial No. 624,131.

To all whom it may concern:

Be it known that I, JOSEPH ERNEST BARROWS, subject of the King of Great Britain, residing at "Sunny Meade," Station Road, 5 Yardley, in the county of Worcester, England, have invented a new and useful Improvement in Cues for Billiards and Like Games; and I do hereby declare the following to be a full, clear, and exact description 10 of the same.

My invention comprises improvements in cues for billiards and like games and refers to that class of wood cues which are longitudinally divided into two parts, these parts 15 being secured around a central metal strengthening piece; and has for its object to provide a more rigid and better balanced cue than those heretofore used.

According to my invention in a wooden 20 cue divided longitudinally into two halves I employ a central metal tube of square, round, or equivalent section, surrounded with a casing of suitable flexible material; all being so secured together that the two 25 wooden parts adhere together and adhere to the tube which is thus prevented from moving longitudinally.

Referring to the drawings:—Figure 1. is an elevation with the wooden portion partly 30 in section, of a billiard cue, according to my invention, the cue being broken into short lengths to facilitate illustration. Fig. 2. is a similar view on a larger scale, part being in longitudinal section. Fig. 3. shows a 35 short length of tubing removed showing the manner of winding the tape around same, while Fig. 4. is a transverse section at A. B. in Fig. 2. Fig. 5. is a section of the top end of the cue.

40 In carrying my invention into practice as illustrated upon the accompanying drawings, the cue is formed from two strips of wood *a*, *a*, each of half round section and adapted when placed together to provide a 45 cue of normal tapered form. In the flat face of each of the half round strips I cut a longitudinal groove of half round section and say of one quarter inch diameter and extending substantially from end to end of 50 the cue. In these central recesses I place a thin steel, german silver, or other metal tube *b*, the two strips being secured together and to the tube in such manner that the tube cannot move longitudinally within the cue. 55 To cause the tube to firmly adhere to the

wood I surround the tube with a covering of textile material, paper, or other flexible material, which may be tightly secured around the tube, or the tube may be previously coated with adhesive to cause the covering to firmly adhere to same. As shown, the covering is in the form of cotton tape *c* previously impregnated with adhesive which is tightly bound around the tube, and which may be coated with size. The covered tube 60 is then placed between the wooden strips to which it is secured by suitable adhesive, and the two wooden parts suitably secured together around the tube. By making the tube of the same weight as the wood removed 65 from the center of the cue, the original balance of the cue is retained; while the tube strengthens and stiffens the cue, and also tends to keep the cue straight, or restore 70 same to a straight line if accidentally warped. Any desired balance of the cue 75 may be obtained by suitably proportioning the weight of the tube to the wood removed from the center of the cue. If a heavier tube is used the forward end of the cue will 80 be heavier, while the opposite result is obtained with a lighter tube.

As shown by Fig. 5 the tube is not continued to the end of the wood, a shouldered 85 plug *e* being inserted. This shouldered plug *e* has a reduced part *e*¹, which fits inside the tube, the main diameter or part corresponding with the hole in the wood, making practically a solid inside rod to the tube as 90 in an ordinary cue.

Any suitable means may be employed to 95 secure the tip *d* on the end of the cue.

What I claim then is:

1. In a cue for billiards and like games, the combination of a casing consisting of 95 two wooden parts each of semi-circular form in section, and having a semi-circular groove extending longitudinally along their flat surfaces from end to end thereof, a central tube located within the aforesaid grooves 100 when the two halves of the casing are placed together but terminating at a distance from the narrow end of the wooden casing, and means for securing said tubes to the wooden parts in such a manner as to prevent relative 105 longitudinal movement between them; a wooden plug adapted to fit within the grooves at the narrow end of the casing in the part not occupied by the tube and against the forward end of which the rear 110

end of said plug abuts, and a reduced shank on said plug fitting within the front end of the tube; substantially as set forth.

2. In a cue for billiards and like games, the combination of a casing consisting of two wooden parts each of semi-circular form in section and having a semi-circular groove extending longitudinally along their flat surfaces, a central tube located within the aforesaid grooves when the two halves of the cue are placed together and flexible material disposed around the tube and between said tube and the grooves, said flexible material being impregnated with adhesive in such manner as to secure the tube to the casing, substantially as set forth.

3. In a cue for billiards and like games, the combination of a casing consisting of

two wooden parts each of semi-circular form in section and having a semi-circular groove 20 extending longitudinally along their flat surfaces, a central tube located within the aforesaid grooves when the two halves of the cue are placed together; and a length of flexible tape wound spirally around the exterior of the tube, such tape being impregnated with adhesive in such manner as to secure the tube to the casing; substantially as set forth.

In testimony whereof, I have signed my 30 name to this specification in the presence of two subscribing witnesses.

JOSEPH ERNEST BARROWS.
